UNITED STATES PATENT OFFICE.

FRANK D. LEWIS, OF WEST ORANGE, NEW JERSEY, ASSIGNOR TO PATHÉ PHONOGRAPH AND RADIO CORPORATION, OF BROOKLYN, NEW YORK, A CORPORATION OF NEW YORK

ACOUSTICAL APPARATUS.

Application filed November 14, 1924. Serial No. 749,936.

To all whom it may concern:

Be it known that I, FRANK D. LEWIS, a citizen of the United States, and a resident of West Orange, in the county of Essex and State of New Jersey, have invented certain new and useful Improvements in Acoustical Apparatus, of which the following is a specification.

My invention relates broadly to acoustical apparatus and more particularly to a construction of combined phonograph reproducer and recorder and electromagnetic sound reproducing and recording apparatus.

The object of my invention is to provide a device for connection to a phonograph which embodies an integral loud speaker for a radio receiving apparatus and a phonograph recording and reproducing device.

Another object of the invention is to provide a tone arm attachment for existing phonographs or a mounting adapted to be installed as a permanent fitting upon phonographs as manufactured for the reproduction of received radio broadcast signals or for the reproduction of phonograph records and for the further purpose of recording upon a phonograph record incoming radio signaling energy.

Still another object of my invention is the provision of an integral structure forming both a radio loud speaker and a phonograph reproducer or recorder wherein means are provided by which the structure may be employed independently for one or another of the said functions without impairing the efficiency or operating qualities of the structure when serving in any of the said functions.

My invention further resides in the arrangement of parts of a combined radio loud speaker and phonograph reproducer and recorder having a rotary valve device for selecting the particular function which is to be employed in the apparatus to the exclusion of other functions.

My invention also has for an object the construction of a unit for connection upon the tone arm of a phonograph including an electromagnetic operating device and diaphragm and a phonograph diaphragm with means for eliminating sympathetic vibrations in one or the other of the dia-

phragms when only one of said diaphragms is being usefully employed.

Still another object of the invention is to provide an adjustable balancing device for a combined unit as herein described whereby the pressure of the recording or reproducing stylus upon the sound record may be regulated.

A still further object of the invention is the provision of an auxiliary weight carrying arm, disposed upon the electromagnetic receiver portion of a combination radio loud speaker and a phonograph sound box unit and stylus which is adapted to be lowered in position upon a record disk for guiding the sound box and stylus unit with respect to the record during the process of recording incoming radio signaling energy upon the record, for subsequent reproduction.

Still further objects of the invention reside in the construction and arrangement of parts of the unit as will more fully appear in the specification hereinafter following by reference to the accompanying drawings in which:

Figure 1 is a schematic view showing the arrangement of the parts of the reproducer with respect to the phonograph; Fig. 2 is a plan view of the loud speaker and reproducer unit showing the method of mounting the unit on the phonograph tone arm; Fig. 3 is an enlarged diagram looking at the end of the electromagnetic sound reproducer portion of the unit; Fig. 4 is a horizontal section view of the combination unit showing the valve device positioned in such manner that vibrations from the diaphragm of the electromagnetic portion of the device are impressed directly upon the diaphragm of the sound box for the recording of incoming radio signaling energy; Fig. 5 shows the positioning of the valve device in the unit for directing the received radio signaling energy directly into the tone arm of the phonograph for the acoustical reproduction thereof; Fig. 6 shows the positioning of the valve device for the reproduction of sound from a sound record by means of the phonograph sound box and tone arm into which the reproduced sound is directed; Fig. 7 is a side view of the unit partially in

vertical section showing the arrangement of the rotary valve device in the unit; and, Fig. 8 is a diagrammatic view showing the arrangement of the electrical circuits employed in the loud speaker portion of the unit when used as a reproducer of radio signals.

I am aware that it has been proposed heretofore to provide a tubular device which will adapt a radio receiver to the tone arm of a phonograph to enable the sound amplifying horn of the phonograph to be employed in the reproduction of radio concerts but in order to do this it has been necessary to remove the reproducer from the phonograph tone arm and replace it by the adapter. This is an undesirable feature in that a phonograph sound box is a delicate mechanism and might readily be injured in the repeated removal processes. It has also been proposed to provide tone arms for phonographs having a pair of extended branches, one for the phonograph sound box and the other for a telephone receiver. The existence of these branches often introduces undesirable interference and distortion in the reproduction of the sound by reason of the sympathetic vibration of the air columns in the tubes.

By the structure of my invention I have overcome these and other disadvantages inherent in the prior structures.

Referring to the drawings in detail, reference character 1 designates the upper portion of a phonograph. The rotatable record table is indicated by reference character 2 carrying phonograph record 3. Swivel arm 5 is mounted on the phonograph 1 and forms the tone arm for conveying sound from the unit 14 to the amplifying horn in the phonograph. The unit 14 is pivotally secured upon the extremity 4 of the tone arm 5. The unit 14 is supported by means of a laterally extending arm 6 having a substantially T-shaped portion 7 with an extension 8 pivotally supported in the extremity 4 of the tone arm 5. At the end of the arm 6 I provide a slidable weight 9 adjustable in position in the longitudinal slot 11 under control of thumb screw 10. An extension 12 is secured upon unit 14 and connects the unit with the extremity of arm 6, delivering sound through the extension 12, the tubular T-shaped portion 7, the swivel portion 8, the extremity 4 of the tone arm 5, and into the sound amplifying horn. The unit 14 comprises a phonograph sound box 15 and an electro-magnetic sound reproducer 16. The electro-magnetic sound reproducer 16 comprises a casing into one end of which is screwed a supporting end member 17 having a finger grip 18. On the inner face of the end member 17 is mounted a permanent magnet 19 and electromagnets 20 arranged adjacent magnetic diaphragm

21 secured in position about its periphery by means of gasket 22. In order to limit the gap between the faces of the pole pieces of electro-magnets 20 and the diaphragm, I provide limit stops 36 cooperating with projection 37 on casing 16. The electro-magnetic sound operating mechanism contained in the casing 16 is supported adjacent the phonograph sound box 15 by means of the cylindrical portion 23 between the phonograph sound box and the electro-magnetic sound reproducer. The phonograph sound box is secured to the portion 23 by means of screws 24. The sound box contains a diaphragm 25 maintained in position by means of gaskets 26. A rotatable valve 27 is journaled within the portion 23 intermediate the ends of ports 28, 29 and 30. The valve is journaled at 31 and is rotated by means of stem 32 from control handle 33 which projects in the space between the electro-magnetic operating mechanism and the phonograph sound box. In order to indicate on the outside of unit 14 the position of valve 27, I provide an indicating arm 34 adjacent the periphery of rotatable disk and control handle 33.

The phonograph sound box containing diaphragm 25 is operated through lever arm 35 pivoted at 36, the lever being controlled by stylus 37 working upon disk record 3 during either the recording or reproducing process as will be hereinafter described. Leads 38 pass through the end member 17 connecting with the electro-magnets 20 of the electro-magnetic operating mechanism. For purposes of recording incoming signaling energy upon the phonograph record, I provide a recording guide arm 39 upon the casing 16 of the electro-magnetic operating mechanism. The guide arm 39 is pivotally mounted at 40 and is under tension of a spring 41 spiraled around the pivot. The arm 39 has an extension 42 on one end thereof in the form of a cam face adapted to operate with a cam face 44 upon a segmental member 43 secured upon the cylindrical surface of the electro-magnetic operating mechanism casing 16 by means of screws 45 passing through short longitudinal slots. The member 43 may be slid circumferentially by a finger piece 46 to move cam face 44 towards or away from cam face 42 whereupon the position of member 39 will be changed. The member 39 carries a stylus 46. When the member 39 is in lowered position the stylus 46 engages the usual spiraled guide groove formed in the surface of the record.

Reference is made to Wadsworth Patent 1,421,045 dated June 27, 1922, as an example of the type of record to which I refer. The stylus 46 operates to guide the recording stylus 37 in a substantially spiral path over the surface of the record, enabling the move-

ment of stylus 37 to make the desired impression in the record between the guiding groove.

Fig. 8 represents the electrical connections of the unit to a radio receiving apparatus. Electron tube 48 has been shown to designate the last tube of an audio frequency amplifying system having high potential plate battery 47 with the windings 20 of the electro-magnetic sound reproducing mechanism in the output plate circuit. Where it is desired to reproduce the incoming radio concert or lecture at some subsequent time, I position the valve 27 to convey sound waves from diaphragm 21 through port 29, valve 27 and port 30, as represented in Fig. 4. The sound vibrations on diaphragm 21 are therefore impinged upon diaphragm 25 actuating the stylus lever 35. When it is desired to directly reproduce the radio lecture or concert, valve 27 is positioned as represented in Fig. 5, whereby port 29 communicates directly with port 28 and conveys the sound energy to the phonograph sound amplifying horn. When it is desired to utilize the apparatus as a phonograph, the valve 27 is positioned as represented in Fig. 6 so that sound energy from diaphragm 25 is conveyed through ports 30 and 28 to the sound amplifying horn. It will be observed in all cases that the valve 27 serves to cut off those ports which are not employed in either the recording or reproducing process, thereby eliminating interference which may arise from sympathetic vibrations.

The apparatus of this invention may be readily attached to present phonograph installations or it may be installed when the phonograph is originally constructed, providing a universal device for the reproduction of radio concerts or phonograph music, or the direct recording of radio concerts for subsequent phonograph reproduction.

While I have described my invention in certain particular embodiments, I desire that it be understood that modifications may be made and that I intend no limitations upon the invention other than are imposed by the scope of the appended claims.

What I claim and desire to secure by Letters Patent of the United States is as follows:

1. A combined phonograph and electro-magnetic sound reproducing unit, comprising a pivotally mounted tubular arm, an electro-magnetic operating mechanism and a phonograph sound box carried on one extremity of said arm, and means whereby sound generated by said electro-magnetic operating mechanism may be conveyed either directly to said phonograph sound box or to said tubular arm to the exclusion of said sound box.

2. A combined phonograph and electro-magnetic sound reproducing unit, comprising

ing a pivotally mounted tubular arm, an electro-magnetic operating mechanism and a phonograph sound box having a stylus connected therewith and supported on one extremity of said tubular arm, means for supporting said tubular arm with relation to a sound record whereby said stylus is adapted to engage said record for the repeating or reproduction of sound, and means positioned intermediate said electro-magnetic operating mechanism and said phonograph sound box whereby sound generated by said electro-magnetic operating mechanism may be conveyed either directly to said phonograph sound box or to said tubular arm to the exclusion of said sound box.

3. A combined phonograph and electro-magnetic sound reproducing unit, comprising a pivotally mounted tubular arm, an electro-magnetic operating mechanism and a phonograph sound box carried on one extremity of said arm, and a valve mechanism positioned intermediate said tubular arm, said electro-magnetic operating mechanism and said phonograph sound box, whereby sound generated by said electro-magnetic operating mechanism or said phonograph sound box may be independently conveyed to said tubular arm to the exclusion of either said phonograph sound box or said electro-magnetic operating mechanism.

4. A combined phonograph reproducer or recorder and an electro-magnetic sound reproducing unit, comprising a pivotally mounted sound conveying tubular arm, an electro-magnetic operating mechanism and a phonograph sound box carried on one extremity of said arm, a short tubular connecting member disposed between said electro-magnetic operating mechanism and said phonograph sound box, inter-communicating ports in said member, a port in said member arranged to convey sound to said tubular arm, and a valve mechanism at the junction of said ports whereby sound generated by said electro-magnetic operating mechanism may be independently directed to said phonograph sound box or to said tubular arm.

5. A combined phonograph and electro-magnetic sound reproducing unit, comprising a pivotally mounted tubular arm, a substantially T-shaped casting carried on the end thereof, an electro-magnetic operating mechanism carried in one end of said T-shaped casting and a phonograph sound box carried in the other end of said T-shaped casting, and means centrally disposed in said T-shaped casting whereby sound generated by said electro-magnetic operating mechanism may be conveyed either directly to said phonograph sound box or to said tubular arm to the exclusion of said sound box.

6. A combined phonograph reproducer or recorder and an electro-magnetic sound re-

producing unit, comprising a pivotally mounted sound conveying tubular arm, a phonograph turn table for carrying a phonograph record adjacent said arm, an electro-magnetic operating mechanism and a phonograph sound box carried on one extremity of said arm, a guiding stylus positioned adjacent said electro-magnetic operating mechanism and adapted to be lowered into or raised from engagement with said record, and means whereby sound generated by said electro-magnetic operating mechanism may be conveyed either directly to said phonograph sound box for recording or to said tubular arm for reproduction to the exclusion of said sound box.

7. A combined phonograph and electro-magnetic sound reproducing and recording unit, comprising in combination with a phonograph record, a pivotally mounted tubular arm, an electro-magnetic operating mechanism, a phonograph sound box having a recording and reproducing stylus adjacent thereto and carried on one extremity of said arm, a record guiding stylus mounted adjacent said electro-magnetic operating mechanism and adapted to be raised or lowered out of or into engagement with said record,

and means whereby sound generated by said electro-magnetic operating mechanism may be conveyed either directly to said phonograph sound box for recording or to said tubular arm to the exclusion of said sound box for reproduction. 30

8. A combined phonograph reproducer or recorder and an electro-magnetic sound reproducing unit, comprising in combination with a carrier for a phonograph record, a pivotally mounted sound conveying tubular arm, an electro-magnetic operating mechanism and a phonograph sound box having a stylus carried on one extremity of said arm, a valve between said arm, said electro-magnetic operating mechanism and said sound box, and an adjustable balancing weight carried by the other end of said arm whereby said stylus may be engaged with predetermined pressure against a record on said carrier and sound generated by said electro-magnetic operating mechanism selectively directed by said valve to said phonograph sound box for recording or to said tubular arm. 40

50 In testimony whereof I hereby affix my 55
signature.

FRANK D. LEWIS
